UNITED STATES PATENT OFFICE.

MAYOTTA BROWNE, OF CARMEL-BY-THE-SEA, CALIFORNIA.

DESIGN FOR A DOLL.

Application filed February 19, 1924. Serial No. 8,676. Term of patent 3½ years.

To all whom it may concern:

Be it known that I, MAYOTTA BROWNE, a citizen of the United States, and a resident of Carmel-by-the-Sea, county of Monterey, State of California, have invented a new, original, and ornamental Design for a Doll, of which the following is a specification, reference being had to the accompanying drawings, forming part thereof.

I claim:

The ornamental design for a doll substantially as shown.

MAYOTTA BROWNE.
